UNITED STATES PATENT OFFICE.

BASIL E. HAYES, OF COMSTOCK, MICHIGAN, ASSIGNOR TO RED EAGLES, SUPREME COUNCIL, INCORPORATED, OF KALAMAZOO, MICHIGAN.

DESIGN FOR A BADGE.

43,501.

Specification for Design.

Patented Feb. 4, 1913.

Application filed October 28, 1912. Serial No. 728,290. Term of patent 14 years.

To all whom it may concern:

Be it known that I, BASIL E. HAYES, a citizen of the United States, residing at the village of Comstock, in the county of Kalamazoo, in the State of Michigan, have invented a new, original, and ornamental Design for a Badge.

My new, original and ornamental design for a badge is clearly illustrated in the accompanying drawing which is a front view thereof.

I claim:

The ornamental design for a badge as shown.

BASIL E. HAYES.

Witnesses:

LUELLA G. GREENFIELD,
M. P. WOODRUFF.
